UNITED STATES PATENT OFFICE.

GARDNER W. PROUTY, OF LITTLETON, MASSACHUSETTS, ASSIGNOR TO THE
W. T. C. MACALLEN COMPANY, OF BOSTON, MASSACHUSETTS.

DESIGN FOR A CAP FOR ELECTRICAL INSULATORS.

SPECIFICATION forming part of Design No. 30,339, dated March 14, 1899.

Application filed February 7, 1899. Serial No. 704,859. Term of patent 14 years.

To all whom it may concern:

Be it known that I, GARDNER W. PROUTY, a citizen of the United States, residing at Littleton, in the county of Middlesex and State 5 of Massachusetts, have invented and produced a new and original Design for Caps for Electrical Insulators, of which the following is a specification, reference being had therein to the accompanying drawings.

10 Figure 1 of the drawings shows in side elevation part of an electrical insulator formed with a cap embodying my design, Fig. 2 shows in plan the said cap.

15 The characteristic features of my design are the rounded upper surface 1 of the cap, the same resembling part of a sphere or

spheroid, and the circular series of cylindrical or turret-like projections 2 2.

The stem to which in practice the cap is connected is omitted from the present drawings, since my design has no reference thereto.

I claim as my invention—

The design for a cap for electrical insulators characterized by the foregoing features and substantially as shown and described. 25

In testimony whereof I affix my signature in presence of two witnesses.

GARDNER W. PROUTY.
